UNITED STATES PATENT OFFICE.

ANTHONY J. STOUGES, OF QUEENS VILLAGE, NEW YORK, ASSIGNOR TO MERGENTHALER LINOTYPE COMPANY, A CORPORATION OF NEW YORK.

SLUG-CASTING MACHINE.

Application filed January 19, 1926. Serial No. 82,184.

My invention relates to slug casting machines, such as linotype machines of the general organization represented in U. S. Letters Patent to O. Mergenthaler, No. 436,532, 5 wherein a melting pot movable to and from the casting position is arranged to deliver molten metal into a slotted mold and up against a composed line of matrices to produce a type bar or slug bearing on its edge 10 type characters corresponding to the intaglio characters of the matrices. In these machines, the molten metal is introduced into the mold by means of a spring-actuated pump piston or plunger arranged within the 15 pot and controlled in its action by a rotary cam, which, as well known, makes one complete rotation for each cycle of operation of the machine. The cam is so shaped as normally to maintain the pump plunger in a 20 raised position out of action, but in one portion of its circumference it is formed with a depression, which at the proper time permits the plunger to descend under the influence of its actuating spring to force the 25 metal into the mold, it being understood in this connection that the distance the plunger descends is largely determined by the amount of metal it displaces, rather than by the depth of the depression in the cam. 30 Since the slugs produced on modern machines vary widely in size (both as regards length and thickness), it is evident that the active stroke of the plunger will vary correspondingly, assuming, of course, that the 35 metal be kept at a constant level within the pot. Thus, when casting short slugs of the thinner variety, the plunger descends only a short distance as compared with the distance it is required to travel when casting 40 long slugs of the thicker variety. In practice, it has been found that this variable condition, aggravated by slight imperfections of adjustment, wearing of the parts, and other causes, permits the recession of the 45 pot to take place before the cam regains its control of the plunger, with the result that the latter is allowed to drop again and squirt molten metal from the pot in an objectionable and even dangerous manner. 50 The present invention is intended to obviate the foregoing difficulties, and contemplates means for establishing the proper relation between the plunger and cam during casting in order to insure the raising 55 of the plunger before the pot breaks its en-

gagement with the mold. To this end, specifically, the plunger is provided with a variable by-pass, whereby it is allowed to make a full downward stroke in casting all slugs, irrespective of size. In the embodiment illustrated, the plunger is provided with a recessed plug screwed into the bottom thereof and capable of adjustment to vary the size of the by-pass according to the size of the slugs to be cast. 60

In the accompanying drawing, I have shown my invention only in preferred form and by way of example, and as applied to a line casting machine, but obviously many changes and alterations may be made therein and in its mode of adaptation, without departure from its spirit. Generally speaking, I desire it to be understood that I do not wish to limit myself to any specific form or embodiment, except in so far as such 70 limitations are specified in the claims. 75

In the drawings:

Fig. 1 is a vertical section through the casting mechanism, showing the parts in casting position prior to the descent of the 80 pot plunger;

Fig. 2 is an enlarged vertical section taken through the improved plunger;

Fig. 3 is a horizontal section, taken on line 3-3 of Fig. 2;

Fig. 4 is a view similar to Fig. 3, showing the plug turned to decrease the size of the by-pass; and

Fig. 5 is a diagrammatic view, showing a relation of the pot plunger roller to the 90 recessed portion of the cam.

In Fig. 1, the parts are shown in the relative positions they occupy just prior to the commencements of the casting operation, the slotted mold A carried by the rotary disc A' being closed at the front by the composed matrix line X, which is presented momentarily thereto by the first elevator B, and at the rear by the mouthpiece of the melting pot C, which contains a supply of 95 type metal maintained in a molten condition by means of a suitable burner (not shown). The pot C is mounted in a jacket or rocking frame C² movable to and fro under the control of the edge cam E, and is 100 formed with a throat or passage C³ through which the metal is forced into the mold by a spring-actuated plunger D, the latter being arranged to reciprocate within the pot well or cylinder C⁴ communicating with the 105

110

throat C³. The plunger D is connected by means of a rod or link D' to the long arm of a bell crank lever D² having a sleeve portion D³ journaled on a fixed transverse rod 5 D⁴ of the machine frame and provided with an arm D⁵ extending laterally beneath a second lever D⁶, which is also journaled on the rod D⁴ and connected at its free end to a pull spring D⁷. The latter is anchored to 10 the machine frame and actuates the plunger D through the connections just described. The shorter arm of the bell crank D² is provided with a roller D⁸ arranged to track upon the periphery of the usual rotary cam 15 D⁹ fast to the main shaft of the machine. As well understood, the peripheral face of this cam is concentric throughout, except at one portion of its circumference where it is cut away or formed with a depression D¹⁰. 20 When the machine is at rest the roller D⁸ is in contact with the concentric portion of the cam D⁹, so that the plunger D is maintained in its raised or inoperative position (shown in Fig. 1). This condition obtains until the 25 casting period arrives, when the cam rotating in the direction indicated brings the downwardly sloping surface d of the depression D¹⁰ into engagement with the roller D⁸, which then quickly descends along such 30 surface toward the bottom of the depression, thus permitting the spring D⁷ to depress the plunger and force a charge of molten metal into the mold. As the cam continues to rotate, the roller D⁸ is engaged sooner or 35 later by the upwardly sloping surface D¹¹ of the depression and the parts thereby more gradually restored to their original condition to await the next casting operation. The parts so far described, and their 40 construction and mode of operation, are or may be the same as those embodied in the commercial linotype machine and in themselves constitute no part of the present invention. It will be understood that, during the slug 45 casting period, the roller D⁸ will seldom reach the bottom of the depression D¹⁰, due to the fact that the plunger D will be arrested in its descent at one level or another according to the volume of metal it displaces 50 in effecting the cast. In casting slugs of the larger sizes, the plunger of course sinks well down in the pot well C⁴ and the roller D⁸ is thus brought quite close to, if not at, the bottom of the depression D¹⁰, so that it 55 (the roller) is in position to be quickly engaged by the cam surface D¹¹ after casting (see Fig. 5). On the other hand, in casting slugs of the smaller sizes (particularly if the pot is filled to its capacity), the plunger 60 is sustained at a much higher level, so that the cycle of operation is allowed to proceed for a considerable period after casting before the roller D⁸ is engaged by the cam surface D¹¹ and the downward pressure of the 65 plunger relieved. This delay of the cam

surface in picking up the plunger has given rise to the difficulties hereinbefore pointed out, and the present invention contemplates certain improvements whereby the plunger is allowed to seek a common level in its descent, irrespective of the quantity of metal which it displaces, and in so doing to locate the roller D⁸ in proper relation to the cam surface D¹¹ to insure the lifting of the plunger within the time limit permitted. 70 In the preferred embodiment illustrated, the plunger D is provided with a by-pass arranged to permit a small amount of molten metal to escape therethrough during its downstroke. Thus at its lower end, the 75 plunger is provided with an internally threaded neck portion D¹² formed with ports or apertures D¹³, and into said neck portion there is screwed a valve plug D¹⁴ formed with a T-shaped port or passage D¹⁵, arranged to register with the apertures D¹³ and in constant communication with the open interior of the hollow plunger. The plug D¹⁴ is provided with a nut D¹⁶ which may be screwed up against the neck portion D¹² to lock the plug in its different adjusted 80 positions. With this arrangement, the size of the by-pass may be varied to suit the casting conditions, or it may be shut off entirely, if desired, by a slight turn of the 85 plug D¹⁴ in either direction. As a result, the active stroke of the plunger may be regulated so as to insure the raising of the plunger prior to the recession of the pot, 90 without regard to the size of the slugs to be cast. Of course, in casting the larger slugs, the by-pass could just as well be closed, since the volume of metal displaced permits the plunger to descend far enough to bring the roller D⁸ under proper control 95 of the cam surface D¹¹ within the time limit allowed. By properly adjusting the by-pass valve, the working stroke of the plunger may be made substantially uniform for all 100 sizes of slugs. It is also pointed out that this adjusting feature, as well as the angular 105 nature of the by-pass, permits the ports to be of much greater diameter than might otherwise be possible, and hence they can be more easily cleaned and are less susceptible to clogging. 110 As before stated, I have herein shown my invention merely in preferred form and by way of example, but obviously many changes and variations may be made therein which will still be comprised within its scope. For instance, while it is particularly advantageous to locate the by-pass in the pump plunger, as above described, it would be entirely feasible to locate said by-pass in the pump well or the pot throat, the essential idea being to permit the molten metal to escape from the pressure chamber into the supply chamber during the active stroke of 115 the pump plunger so that the latter may de- 120 125 130

scend far enough to come under proper control of its actuating cam. It is, therefore, understood that I do not wish to limit myself to any particular form or embodiment except in so far as such limitations are set forth in the claims.

Having thus described my invention, its construction and mode of operation, what I claim and desire to secure by Letters Patent of the United States is as follows:

1. In a slug casting machine, the combination of a melting pot containing a pump well, a pump plunger arranged to reciprocate in said well, and a constantly open by-pass arranged to permit the escape of metal past the plunger throughout its active stroke, for the purpose described.

2. In a slug casting machine, the combination of a melting pot containing a pump well, a pump plunger arranged to reciprocate in said well, and a constantly open by-pass to permit the escape of metal from the pressure chamber into the supply chamber of the pot throughout the active stroke of the plunger.

3. In a slug casting machine, the combination of a melting pot containing a pump well, a pump plunger arranged to reciprocate in said well, a constantly open by-pass to permit the escape of metal from the pressure chamber into the supply chamber of the pot throughout the active stroke of the plunger, and means for regulating the size of the by-pass according to the volume of metal required to be displaced by the plunger in the casting operation.

4. In a slug casting machine, the combination of a melting pot containing a pump well, a pump plunger arranged to reciprocate in said well, a by-pass formed in said plunger to permit the escape of metal past the same during its active stroke, and means

for adjusting the size of the by-pass according to the volume of metal required to be displaced by the plunger in the casting 45 operation.

5. In a slug casting machine, the combination of a melting pot containing a pump well, a pump plunger arranged to reciprocate in said well, a by-pass formed in said plunger to permit the escape of metal past the same during its active stroke, and a valve plug adjustable at will to regulate the size of the by-pass.

6. In a slug casting machine, the combination of a melting pot containing a pump well, a pump plunger arranged to reciprocate in said well, a by-pass formed in said plunger to permit the escape of metal past the same during its active stroke, and means 60 for closing the by-pass when desired.

7. In a slug casting machine, the combination of a melting pot containing a pump well, a pump plunger arranged to reciprocate in said well, a by-pass formed in said plunger to permit the escape of metal past the same during its active stroke, a valve plug adjustable at will to regulate the size of the by-pass, and means for locking the plug in its adjusted positions.

8. In a slug casting machine, the combination of a melting pot containing a pump well, a spring-actuated plunger arranged to reciprocate in said well, a cam for controlling the active stroke of the plunger, a lever connected to the plunger and arranged to cooperate with said cam, and a constantly open by-pass formed in said plunger and governing the extent of its active stroke to insure the proper operative relation between the lever and cam.

In testimony whereof, I have affixed my signature hereto.

ANTHONY J. STOUGES.
